SMOKING PIPE

Frederick Myers, Charlestown, Mass.

Application November 24, 1948, Serial No. 61,757

2 Claims. (Cl. 131—202)

1

This invention relates to smoking pipes and has for its general object the provision of simple and inexpensive means whereby the pipe may conveniently be cleaned and the products of combustion, commonly known as sludge, nicotine, tar, etc., may readily be removed, and also the provision of means whereby such combustion products may be removed from the tobacco fumes before such fumes enter the pipe stem.

In the drawings accompanying and forming a part of this application,

Figure 1 is a central longitudinal section of a pipe embodying my invention.

Fig. 2 is a similar section of a modification.

Fig. 3 is an elevation on an enlarged scale of the cup hereinafter referred to.

Fig. 4 is a central longitudinal section of the condensation chamber and a portion of the tubular member affording a duct between the bowl and mouthpiece of the pipe.

Fig. 5 is a section on a still larger scale of the filter provided for the inner end of the condenser chamber.

Fig. 6 is an end view on the same scale as Fig. 5 of said filter.

In the particular drawings selected for more fully disclosing my invention and the underlying principle thereof, said drawings to be considered as illustrative, merely, and not restrictive, 10 represents the bowl portion of the pipe which consists of three sections, namely, the bowl section 11; the socket section 12 at the lowermost end of the bowl portion and the section 13 intermediate the other two. Secured into the intermediate section in any suitable manner by screw threads 14, as shown, or frictionally, is a tubular member 15 having an outwardly flaring upper portion 16, the lower end of said tubular member extending into the socket section aforesaid.

A cup 17 is disposed in the socket section 12 and held in operative position by any suitable means, such as the bolt 18, shown in the present instance, the inner end of said bolt being engaged in the peripheral groove 19 formed in the cup. The compression spring 20 forces the end of the bolt in the groove and by means of the button or finger piece 18' the bolt may be moved axially to release the cup. Interposed between the cup and the intermediate section of the pipe portion is a compression spring 21 so disposed as to urge the cup outwardly when the bolt is moved to the right. The cup may be lined with a sheet of absorbent material 22 which may readily be removed when the cup is sprung out of its socket and replaced by a clean sheet.

2

The stem portion 23 integral with said bowl portion, is provided with the usual duct 24 between the bowl proper and the mouthpiece 25.

After the pipe has been used for a while, the cup is sprung out of its socket, as above described, cleaned and replaced, but the spring 21 is so arranged that it will remain in the socket section 12 after the cup has been removed therefrom. In the present instance, the uppermost 10 spire 26 of the spring is of greater diameter than the others and extends over the flaring edges of the cup, thus being in frictional engagement with the wall of the socket section 12.

As shown in Fig. 2, a tubular member 27 is 15 disposed in the stem portion in register with the central longitudinal bore of the mouthpiece. The inner end of said tubular member which may be of aluminum, or other suitable metal, is enlarged both radially and axially to provide an 20 expansion chamber 28, the function of which is to cool the smoke before it enters the mouthpiece and the inner end of said chamber is provided with filter means 29 of any suitable type. The filter means is frictionally engaged with the end 25 of the expansion chamber and, as shown in Figs. 4 and 5, the periphery of the filter may be grooved, as indicated at 30, to receive a peripheral rib 31 formed on the inner surface of the outer end of the expansion chamber.

30 In the manufacture of the pipe, the bore 32 in which the bolt is disposed, is made by boring from the forward end of the bowl portion and that portion of such bore to the left of the socket section is then filled with a plug 33.

35 In the form shown in Figure 2, the stem portion is bored from end to end to form the duct 34 and then said duct is reamed out or otherwise enlarged sufficiently to accommodate the expansion chamber 28. The tubular member 27 may

40 either be integral with the enlargement thereof which forms the condensation chamber or else rigidly attached thereto by electric welding or otherwise. The rearward end of said tubular member abuts the forward end of the mouthpiece and, as the enlarged end thereof snugly fits the bore in which it is disposed, the member 27 will remain fixedly in the position shown in Fig. 2.

Having thus described illustrative embodiments of my invention without, however, limiting the same thereto, what I claim and desire to secure by Letters Patent is:

50 1. A smoking pipe comprising in combination, a bowl, a mouthpiece, a stem portion provided with a duct between said bowl and mouthpiece,

55

a removable upwardly-extending open-ended cup disposed beneath said bowl, said bowl having a bore communicating with said cup and the outer periphery of said cup being provided with a groove, a spiral compression spring interposed between said bowl and said cup, said spring urging said cup outwardly, a spring pressed bolt having its outer end in engagement with said groove for locking said cup in operative position against the action of said compression spring and manually actuated means for moving said bolt axially to release said cup.

2. A smoking pipe comprising in combination, a bowl section, a socket section at the lowermost end thereof, a mouthpiece, a stem portion provided with a duct between said bowl section and mouthpiece, a removable cup disposed in said socket section, said bowl section having a bore communicating with said cup, a compression spring interposed between said bowl section and said cup, said spring urging said cup outwardly, the uppermost spire of said spring being of greater diameter than the others and being disposed for frictional engagement with the wall of said socket section whereby said spring will remain 25

in said socket section after the cup has been removed therefrom, and manually actuated means for locking said cup in operative position against the action of said spring.

FREDERICK MYERS.
